UNITED STATES PATENT OFFICE.

ALFRED F. McCOLLUM, OF BLOOMSBURG, PENNSYLVANIA, ASSIGNOR OF THREE-FIFTHS
TO JAMES MAGEE, 2D, OF BLOOMSBURG, PENNSYLVANIA.

PILE-WIRE.

1,130,617.

Specification of Letters Patent.

Patented Mar. 2, 1915.

Application filed February 28, 1914. Serial No. 821,690.

To all whom it may concern:

Be it known that I, ALFRED F. McCOLLUM, a citizen of the United States, residing in Bloomsburg, Columbia county, Pennsylvania, have invented certain Improvements in Pile-Wire, of which the following is a specification.

My invention consists of an improved form of pile wire for use in looms for the manufacture of pile fabrics and is particularly serviceable in the weaving of those fabrics in which the wires are inserted transversely to the warp and over which the latter is looped to form the pile of the fabric.

As herein illustrated my invention is especially constructed for use in looms provided with pile cutting mechanism including a pile cutting knife and a series of grooved wires in which said knife is movable.

Heretofore the wires used had rounded convexed bottom portions which rested on the body warp of the fabric and were often tilted or up-set, before they were bound in the warp, by the pull of the warp during the change of the sheds with the result that irregular rows of pile were frequently caused.

One object of my invention therefore is to so construct the pile wires that they cannot easily be upset or turned over after they have been inserted in the fabric, it being also desired that the wires shall be so constructed as not to injure the fabric during their insertion and withdrawal.

A further object of the invention is to provide said wires with means for guiding or insuring the proper entry of the pile-cutting knives into their grooves.

These objects I attain as hereinafter set forth reference being had to the accompanying drawings in which,

Figure 1, is a side elevation of a pile wire made in accordance to my invention; Figs. 2 and 3, are enlarged transverse sections taken respectively on the lines *a—a* and *b—b* Fig. 1; Fig. 4, is an enlarged plan of one end of the wire shown in Fig. 1; Fig. 5, is a sectional elevation taken on the line *c—c* Fig. 4; Fig. 6, is an enlarged fragmentary transverse section taken through the weft of a fabric and through wires which are made according to my invention; and Figs. 7 and 8, are enlarged cross sections of modified forms of wire.

Referring to the drawings, the wire 1 is longitudinally grooved at 2 and is secured to a jack head 3 for facilitating its insertion and withdrawal in the usual manner during the weaving of a fabric. The wire 1 has a base surface which may be substantially flat as shown at 4 in the main views of drawing and side surfaces 5 and 6 which are inclined to the base surface 4 as shown in Fig. 3.

The wire 1 is provided with a knife-guiding section or extension 7 which may be brazed or otherwise secured thereto or may be made integral therewith. This guiding section has an inclined top surface 8 which as shown in Fig. 2, is flush with and forms a continuation of one side of the groove 2.

In order to prevent the ends of the wires from injuring the yarn of the fabric during their insertion under the pile yarn, I form them adjacent their ends with a slight upward curve as shown in Fig. 1 from *X* to *Y* and also give the ends a more abrupt upward bend as shown from *Y* to *Y'*. The top surfaces of the wire ends are ground or otherwise shaped as indicated at 9 so that the surfaces will be smooth.

In order that the novel features of my invention may be fully understood I will describe the same in connection with its use in the manufacture of a fabric in which the pile is formed by looping pile-forming warp threads over the wires. The wires are inserted within the warp sheds in the direction of the arrow *X'* Fig. 1, so that the pile warp will be looped over them after they have been "beat up" as shown in Fig. 6; the wires being shown in their "beat up" positions and resting on the ground weave 10. The tension on the pile warp acts in the direction of the arrow *Z* and, prior to my invention has frequently caused the last wire "beat up" by the lay to be upset. By having the base of the wire flat or so shaped that both its edges 11 and 12 rest directly on the ground weave and by also having the surfaces 5 and 6 and hence the body of the wire inclined from said edges in a direction opposite to that of the pull of the pile warp, the wires will tend to retain their proper positions in the fabric and cannot be easily upset. This result is attained because before the wire could upset it would be necessary for the pull of the pile yarn to turn the wire on the edge 11 as a fulcrum and since the shape of each wire causes it to lean in a

direction opposite to that indicated by the arrow Z, the amount of this tension on the pile yarn is not sufficient to turn the wires from their proper positions.

5 The pile warp which is looped over the wire may be cut by a pile-cutting knife 13 of any suitable construction, which after being lowered into the grooves of wires is moved longitudinally to cut the loops. By 10 having the guiding section 7 extending part way of the length of the wire and projecting above the top thereof as shown in Figs. 2 and 6, the surface 8 will act as a deflector during the downward movement of the 15 knife to guide the latter insuring that it enters the groove. This is a valuable feature of my invention, for hitherto the fabrics and knives have often been injured by failure of the knives to properly enter the 20 grooves during their downward movement. In order to further insure the entrance of the knife I widen that portion of the groove immediately adjacent the part 7.

25 In Fig. 7 I have shown a pile wire described and claimed in my application for U. S. Patent, Serial No. 848,458, filed July 1, 1914. This form of wire has its base slightly concaved, so that its edges 11^a and 12^a will contact with the ground weave 10 to firmly 30 seat the wire.

35 The form of wire shown in Fig. 8 is particularly serviceable in weaving uncut pile fabrics, such as body Brussels and tapestry Brussels or in the weaving of cut pile fabrics where the pile-cutting knives are secured to the ends of the pile wires as is the ordinary method of making tapestry velvet and Wilton carpets. In this case the base of the 40 wire resting on the body or ground weave warps is made flat as shown at 4^b and the sides may be made perpendicular thereto or may be inclined if they are to be used where

the warp is under great tension. By having the base 4^b flat the wire cannot be easily tilted but will retain its proper position 15 even during its withdrawal so that if a knife is attached to its end it will always cut in the desired path.

I claim:—

1. A pile wire for use in the manufacture 50 of pile fabrics, having flat side surfaces extending from the base and both inclined in the same direction.

2. A pile wire for use in the manufacture 55 of pile fabrics, having a substantially flat base and side surfaces extending from the latter inclined in the same direction.

3. A pile wire for looms having at least 60 one of its side surfaces inclined to the plane of its base.

4. A pile wire having a grooved body portion and a knife-guiding section, the groove of said body portion being of increased width adjacent the knife-guiding section, and the latter having an inclined 65 surface flush with one side of the groove to insure the entrance of the knife into said groove without injury to the cutting edge thereof.

5. A pile wire, for use in the weaving of 70 pile fabrics, having that portion which is woven in the fabric formed with a flat base.

6. A pile wire, for use in the weaving of 75 pile fabrics, having that portion which is woven in the fabric provided with a base including at least two edges placed to engage the ground weave of the fabric.

In testimony whereof, I have signed my name to this specification, in the presence of two subscribing witnesses.

ALFRED F. McCOLLUM.
